ASHTRAY

George H. Reimer, Fulton, Ill., assignor to Patent Novelty Company, Fulton, Ill., a corporation of Illinois

Application June 3, 1935, Serial No. 24,664

1 Claim. (Cl. 131—51)

This invention relates to ash trays.

Generally stated, the object of the invention is to provide a novel and improved construction and arrangement whereby an ash tray is not only provided with means for receiving a lighted cigarette, or the ashes therefrom, but is also provided with means for extinguishing a lighted cigarette, as well as for holding a lighted cigarette conveniently a distance above the ash receptacle portion of the tray.

It is also an object to provide certain details and features of construction tending to increase the general efficiency and desirability of an ash tray of this particular character.

To the foregoing and other useful ends, the invention consists in matters hereinafter set forth and claimed and shown in the accompanying drawing, in which—

Fig. 1 is a perspective of an ash tray embodying the principles of the invention.

Fig. 2 is a vertical transverse section on line 2—2 in Fig. 1 of the drawing.

Fig. 3 is a detail perspective view illustrating the method of constructing the tray, showing two of the parts before they are attached together.

Fig. 4 is a similar view showing the said parts attached to each other.

Fig. 5 is a perspective view illustrating the method of extinguishing a lighted cigarette.

As thus illustrated, the invention comprises a tray having a body 1 provided with a centrally depressed portion forming the ash receptacle 2 of the tray. A plate 3 extends across the receptacle, centrally, and is formed with end portions 4 that are inserted through the slots 5 in the side portions of the tray, these end portions then being bent upwardly and clinched on the under side of the tray, as shown in Fig. 4 of the drawing.

It will be seen that the plate 3 has its upper portion provided with a plurality of downwardly tapered notches 6, for receiving a lighted cigarette, as shown in dotted lines in Fig. 1, or for extinguishing a lighted cigarette, as shown in Fig. 5 of the drawing. In other words, these downwardly tapered notches 6 provide edges that will grip a cigarette, or that will cut off the tip or burning portion of the cigarette.

In use, the tray may be placed on a table, or on any other support, in a convenient position to receive the ashes from a burning cigarette, or to receive the cigarette itself, or to extinguish the cigarette, in the manner shown and de-

scribed. The construction is simple and inexpensive, and it will be seen that the notches 6 are preferably radial to a point some distance below the tray, whereby the tongues 7 are also radial to the same point, these tongues being spaced apart to provide the notches 6, which latter are of a width and depth and shape to receive and hold a cigarette, effectively, but practically without any distortion thereof. The edges of the notches, shown and described, are thin enough to practically cut off the burning portion of the cigarette, so that the same may drop into the ash receptacle below. In this way, a partially smoked cigarette is held against dropping into or rolling around in the ashes of the tray and, in addition, the burning portion of the cigarette can be severed therefrom without mashing or squeezing the unburned portion thereof.

It will be seen that the lower edge of the plate 3 is above the bottom of the receptacle 2, so that the ashes may collect in the receptacle without interference by the plate. Cigarette butts can be thrown into the tray and may collect together without interference by the plate.

It will be seen that the upstanding portions 7 of the bridge plate 3 are radial to a point substantially below the bottom of the tray, and that the spaces between these upstanding portions taper downwardly and are also radial to said point below. In addition, it will be seen that the lower edge of the plate 3 is curved or rounded to extend below the plane of the top of the rim of the tray, thus increasing the distance between this edge and the lower ends of the downwardly tapered spaces between the portions 7, giving the plate adequate body strength and rigidity, but with less height above the horizontal plane of the rim portion of the tray, and with the plate 3 disposed in a vertical plane substantially midway between opposite sides of the depression of the tray, in which depression the ashes and cigarette stubs are held. Also, by arranging the upstanding portions 7 radial to a point below, the length of the plate 3, for any given number of downwardly tapered notches between said portions 7, is substantially less than would be the case if the upstanding portions 7 were all exactly vertical, instead of being radial to a point substantially below the tray. Again, it will be seen that the tops of the upstanding portions 7 are on the line of a circle struck from the said point below the tray, and that the upstanding notches between the said up-

standing portions are on the line of a smaller circle struck from the same point, or substantially so, as shown in the drawing.

What I claim as my invention is:

- 5 In a combined ash tray and cigarette holder and extinguisher, a sheet metal body forming the tray, with a substantially flat horizontal rim portion for the top of the tray, slots formed in the said rim portion at opposite sides of the tray, a bridge plate of relatively thin flexible sheet metal disposed in the vertical plane of said slots, provided with reduced end portions formed for insertion through said slots, bent upwardly against the under side of said rim, and
- 10 holding the plate firmly in a vertical plane, said plate having its lower edge curved and rounded longitudinally of the plate, so that said edge is below the plane of the top of the tray, and the upper edge portion of said plate, above the
- 15 upper edges of said reduced end portions, being notched to form downwardly converging and
- 20

downwardly tapering spaces alternating with upstanding portions radial, like the spaces, to a point substantially below the bottom of the tray, the edges of said upstanding portions being adapted to grip a cigarette placed between the edges thereof, to hold the cigarette, and being also adapted to sever the burned portion of the cigarette from the unburned portion thereof, and said tray being formed with a depression 5 to receive the ashes and cigarette stubs, extending equidistant at opposite sides of said plate, with said curved lower edge of the plate disposed a distance above the bottom of said depression, whereby the tops of said upstanding portions are on the line of a circle struck from 10 said point below the tray, and the lower ends of said notches are on the line of a smaller circle struck from the same point, whereby the entire device is composed of only two sections of sheet metal.

GEORGE H. REIMER.
